UNITED STATES PATENT OFFICE.

ALVIN CARROLL GODDARD, OF NEW YORK, N. Y.

FIREPROOF DOOR.

1,100,555.

Specification of Letters Patent. Patented June 16, 1914.

Application filed April 19, 1912. Serial No. 691,778.

To all whom it may concern:

Be it known that I, ALVIN C. GODDARD, a citizen of the United States, and a resident of the city of New York, Richmond Hill, borough of Queens, in the county of Queens and State of New York, have invented a new and Improved Fireproof Door, of which the following is a full, clear, and exact description.

10 The object of the invention is to provide a new and improved fireproof door which is insulated to the full size of the door opening and when subjected to fire is not liable to warp or disintegrate or its sections 15 come apart even should the wooden core be reduced to charcoal. For the purpose mentioned use is made of a wooden core, wooden stile pieces, wooden rail pieces, inner and outer sheet metal coverings and inner and 20 outer layers of asbestos or other insulating material arranged between the core and the inner sheet metal covering and between the inner and outer sheet metal coverings.

25 A practical embodiment of the invention is represented in the accompanying drawings forming a part of this specification, in which similar characters of reference indicate corresponding parts in all the views.

Figure 1 is a perspective view of the wooden core of the door; Fig. 2 is a like view of the same showing the core covered with the inner layer of asbestos and the stile strips in position, one of the stile strips being broken out; Fig. 3 is a like view of the same with the inner sheet metal covering in place on the core and stile pieces, part of the covering being broken out; Fig. 4 is a similar view of the same and showing the rails in place and a portion of the outer layer of asbestos in position; Fig. 5 is an enlarged sectional plan view of the partly finished door, the section being on the line 5—5 of Fig. 3; Fig. 6 is a face view of the fireproof door; Fig. 7 is an enlarged sectional plan view of the same on the line 7—7 of Fig. 6; Fig. 8 is a similar view of the same on the line 8—8 of Fig. 6; Fig. 9 is an enlarged transverse section of the same on the line 9—9 of Fig. 6; Fig. 10 is a perspective view of one corner of the door part, of the molding being broken out; Fig. 11 is an enlarged sectional plan view of a modified form of the fireproof door; and Fig. 12 is a sectional plan view of the door with the insulations omitted.

In manufacturing the fireproof door use

is made of a core A, preferably formed of tongue and groove boards fastened together, as plainly indicated in Fig. 1, and this core A is covered with a layer B of asbestos or other suitable insulating material, and on the layer B are placed stile strips C fastened to the core by fastening devices D, preferably in the form of nails, driven through one of the stile pieces through the core and the other stile piece to be clenched at the outer face thereof, as will be readily understood by reference to Fig. 5. When this has been done the exposed faces of the stile pieces C are covered with a layer B' of asbestos or other insulating material so that the stile pieces are completely inclosed by the insulating material. An inner sheet metal covering E is applied to cover the exposed portions of the layers B and B', the sheet metal covering having overlapping ends E' at the edges, and the top and bottom of the door. The overlapping edges at the sides of the door are fastened to the core A by nails F, as plainly shown in Figs. 3, 4 and 5. The rail pieces G of wood are now placed in position on the inner sheet metal covering E and are fastened to the core by fastening devices H, such as nails driven through the rail pieces and the core A and the sheet metal covering E and clenched at the pointed ends, as indicated in Fig. 9. Outer layers I and I' of asbestos or other suitable material are now placed on the sheet metal covered stiles and the rails G, as plainly indicated in the lower portion of Figs. 4 and 6. Outer metal coverings J in the form of caps are placed over the layers I, and outer sheet metal coverings J' are placed over the coverings I' of the rails G, and the adjacent ends of the outer coverings J and J' are interlocked with each other by double seams J², as plainly indicated in Figs. 8 and 10. Nails or other fastening devices K are preferably employed to fasten the outer metal coverings J to the rail pieces G and the core A under the double seams J², as plainly indicated in Fig. 8, and nails K' may also be used for fastening the flanges J³ of the outer coverings J in position on the stile pieces C (see Fig. 8). Flanges J⁴ along the inner edges of the covered rail pieces G are fastened in place on the rail pieces by nails K², as plainly indicated in Fig. 9. After the parts of the door have been assembled in the manner described then the

usual panel moldings L are placed in position and fastened to the core A, in the usual manner.

From the foregoing it will be seen that by 5 the arrangement described inner and outer layers of insulating material are used and inner and outer sheet metal coverings the inner layer of insulating material being disposed between the core and the inner sheet 10 metal covering while the outer layer of insulating material is disposed between the inner and outer sheet metal coverings. By this arrangement the door is not liable to warp even if subjected to a high heat and 15 the parts of the door are not liable to come apart even should the wooden core A be reduced to charcoal, especially as the outer sheet metal coverings for the stile and rail pieces are locked by the double seams and 20 the inner sheet metal covering completely incloses the core and the stile pieces.

In the modified form shown in Fig. 11 the double seam J² is dispensed with and the outer sheet metal coverings J and J' are 25 simply provided with flanges fitting around the corresponding edges of the stile pieces and rail pieces.

In some types of doors, as shown in Fig. 30 12, the insulations are omitted and the core having stiles and rails is covered by two sheets of metal E and the sides and ends are overlapped at the outer edges of the stiles and top and bottom rails, then the split 35 tubular coverings J in the form of caps are placed over the covered stiles and rails so that the said covered stiles and rails are incased by the second metal coverings J thus

forming a very strong door not liable to have its parts come apart when the door is subjected to high heat. The overlapped 40 sides and ends of the coverings E are fastened in place on the core by nails or other fastening devices F, and similar fastening devices K² are used for fastening the free edges of the coverings J to the stiles and 45 rails.

Having thus described my invention, I claim as new and desire to secure by Letters Patent:—

A fireproof door, comprising a wooden 50 core, wooden stile pieces secured to the said core, inner sheet metal coverings, one for each face of the core and extending over the exposed portion of the core and over the said stile pieces, the coverings being provided 55 with overlapping ends at the sides, top and bottom of the door, wooden rail pieces overlying the said sheet metal covering and secured to the same and the core, sheet metal stile caps incasing the said metal coverings 60 at the stiles, sheet metal rail caps incasing the said rail pieces, the said caps being of split tubular form having inwardly-extending flanges fitting against the inner edges 65 of the stiles and rails, the middle portions of the caps overlying the said overlapping sides and ends of the sheet metal coverings.

In testimony whereof I have signed my name to this specification in the presence of two subscribing witnesses.

ALVIN CARROLL GODDARD.
